COMBINED CIGARETTE CONTAINER AND MATCH HOLDER

Filed Oct. 13, 1944

Judson Craig Eubank INVENTOR

UNITED STATES PATENT OFFICE

139,819

DESIGN FOR A COMBINED CIGARETTE CONTAINER AND MATCH HOLDER

Judson Craig Eubank, New York, N. Y.

Application October 13, 1944, Serial No. 115,758

Term of patent 7 years

(Cl. D85—2)

To all whom it may concern:

Be it known that I, Judson Craig Eubank, a citizen of the United States, residing at New York, in the county of New York and State of New York, have invented a new, original, and ornamental Design for a Combination Cigarette Container and Match Holder, of which the following is a specification, reference being had to the accompanying drawing, forming part thereof:

Fig. 1 is a perspective view of a combination cigarette container and match holder, showing my new design, and

Fig. 2 is a front elevational view thereof.

I claim:

The ornamental design for a combined cigarette container and match holder, substantially as shown.

JUDSON CRAIG EUBANK.
